KNITTING MACHINE

Willis A. Ingalls, Syracuse, N. Y., assignor to
Tompkins Bros. Co., Syracuse, N. Y., a corpora-
tion of New York

Application May 8, 1941, Serial No. 392,540

14 Claims. (Cl. 66—157)

This invention relates to knitting machines, and more especially to brake mechanisms and associated controls for circular spring needle knitting machines.

In conventional machines of this type, the fabric is knitted on a rotary power driven needle cylinder having a ring of spring needles mounted thereon, and as the fabric is knitted, it is taken up or wound up by a take-up mechanism usually mounted above the needle cylinder and arranged for rotation therewith. As conventionally practiced in present day knitting machines of the circular spring needle type, to stop the machine, the power is cut off and the rotating parts coast to a stop. Due to the large mass of the rotating parts such as the needle cylinder and take-up mechanism, an appreciable time is required for these parts to come to a standstill by loss of momentum. Obviously, this delay is detrimental to the efficiency of operation of the machine, and it is especially disadvantageous under some conditions such as when a thread or needle breaks or one of the thread supplies runs out. At these times and others of a more or less emergency nature, an immediate or abrupt stopping of the machine is very desirable.

I have found that the application of braking forces to the needle cylinder and to the take-up mechanism may be employed to considerable advantage in cylindrical spring needle machines of this type and one of the primary objects of the present invention is to provide a novel and effective braking mechanism, and selective controls therefor, to insure quick stopping of the machine without damage to either the machine or to the fabric knitted thereby.

A further object of the invention is to provide a brake and selective control system of the aforementioned character, wherein the driving power is initially applied to the machine through the operation of a manual control which simultaneously releases the brakes for the needle cylinder and take-up mechanism, and maintains these brakes in a released condition until such time as the machine is to be brought to a stop through the operation of certain other manual and/or automatic controls which serve to interrupt the power drive and quickly bring the machine to rest through the aid of the brakes aforesaid.

Another object of the invention is the provision of a simple and effective selective control system of the electric type for interrupting the power drive and simultaneously applying the brakes, said selective control system preferably

including a manually operable control device, a thread operated control device, and a fabric operated control device, each of which control devices is operable independently of the others and serves to interrupt the power drive and simultaneously apply the brakes.

The selective electric control system above referred to insures the maximum protection of the machine against damage, and materially contributes to the production of high quality and high grade fabrics free of imperfections. In addition, through the application of braking force to the take-up mechanism, back-lash of the take-up mechanism is avoided on applications of the braking force to the needle cylinder, thereby minimizing jamming of the needles and other parts of the machine as would otherwise occur.

A further important object of the invention is to provide a special and improved type of thread responsive circuit control device, hereinafter sometimes referred to as the thread stop motion, which is so constructed and arranged as to be actuated by inadvertent breaking of the thread at an unduly weak point, and also by undue tension on the thread or other imperfections therein, and when so actuated, the power drive will be automatically interrupted and the brakes applied. In the case of undue tension on the thread and certain other imperfections, the machine will be automatically stopped without breaking the thread and necessitating rethreading of the machine from the break to the needles and reengagement of the fabric with the needles, as customarily required when a thread breaks in most machines of the present day type. This feature is especially advantageous as the thread reaches the end of the supply on the bobbin, since a new thread supply can be attached to the end of the previous supply before the thread runs out at the end of the needles and the fabric becomes disengaged from the needles.

Still another object of the invention is to provide a new and improved type of fabric responsive circuit control device, hereinafter referred to as the fabric stop motion, which is so constructed and arranged as to be positively actuated when a hole, drop stitch, needle run or other imperfection occurs in the fabric and when so actuated, serves to automatically interrupt the power drive and promptly apply the brakes as hereinbefore stated.

A further object of the invention is to provide thread furnishing instrumentalities arranged between the point of entry of the thread into the needles on the needle cylinder and the thread

stop motion in the thread feed, said furnishing instrumentalities serving to present the thread to the needles in uniform lengths at each needle, while relieving the needles of any drag, thereby eliminating tension on the thread between the furnishing instrumentalities and the needles and confining the tension on that portion of the thread between the furnishing instrumentalities and the source of thread supply where it is most effective to act upon the thread stop motion.

Other and further objects of the invention will be hereinafter described, and the novel features thereof defined by the appended claims.

In the drawings:

Figure 1 is a view, partly in side elevation and partly in vertical section, of the upper portion of a knitting machine embodying the present invention, said upper portion including the main cloth spreader, the take-up mechanism and the brake therefor;

Figure 2 is a view, partly in side elevation and partly in vertical section, of the lower portion of the knitting machine as a continuation of Figure 1, and including the base structure, needle cylinder and brake therefor, and associated stands and control devices;

Figure 3 is an enlarged, fragmentary top plan view of the main power control and cooperating brake actuating instrumentalities for the needle cylinder brake, certain of the latter parts being broken away and shown in section;

Figure 4 is an end elevation of the brake actuating instrumentalities shown in Figure 3 as viewed from the right hand end as shown in that figure, the main power control being shown in outline in broken lines;

Figure 5 is a view, partly in top plan and partly in horizontal section, of the take-up mechanism and brake and associated brake actuating instrumentalities;

Figure 6 is a vertical sectional view taken on the line 6—6 of Figure 5;

Figure 7 is an enlarged vertical sectional view taken on the line 7—7 of Figure 5;

Figures 8 and 9 are enlarged, detail vertical sectional views taken respectively on the lines 8—8 and 9—9 of Figure 3;

Figure 10 is an enlarged, detail top plan view of the main power control with the cover removed and certain other parts omitted, portions of the housing being broken away and shown in section;

Figure 11 is a vertical sectional view taken on the line 11—11 of Figure 10, with the cover applied on the housing, but with other parts omitted;

Figure 12 is a vertical sectional view taken on the line 12—12 of Figure 10, with the cover also applied on the housing, and additionally showing certain magnetically operated trip instrumentalities omitted from Figures 10 and 11;

Figure 13 is a view in top plan of the magnetically controlled trip instrumentalities forming a part of the main power control as shown in Figure 12;

Figure 14 is a detail view, partly in vertical section and partly in side elevation, of one of the thread stop motion devices which forms a part of the selective power and brake control system, with one side of the casing of the stop motion device removed;

Figures 15 and 16 are vertical sectional views taken respectively on the lines 15—15 and 16—16 of Figure 14, with the side of the casing omitted in Figure 14 attached;

Figure 17 is an enlarged, detail fragmentary

top plan view of the thread stop motion device and an associated thread guide known in the trade as a sub-catcher, together with a portion of the circular support on which the stop motion device and sub-catcher are mounted in operative relation to each other, certain parts being broken away and shown in section;

Figures 18 and 19 are fragmentary, detail vertical sectional views taken respectively on the lines 18—18 and 19—19 of Figure 17;

Figure 20 is a fragmentary view in side elevation showing the fabric stop motion device which forms a part of the selective power and brake control system;

Figure 21 is a vertical sectional view taken at one side of the fabric stop motion device of Figure 20 and showing the stop motion device in elevation as viewed substantially tangentially to the needle cylinder;

Figure 22 is a fragmentary vertical sectional view taken on the line 22—22 of Figure 21;

Figure 23 is a fragmentary, somewhat diagrammatic top plan view of a typical setup of thread guides, burrs, sinkers, pressers, etc., as may be used at one regular thread feed and an associated backing thread feed, and particularly showing the thread furnishing wheels and the manner of driving the same by the needles on the needle cylinder;

Figure 24 is a diagrammatic view of a main electric power circuit, and additional electric circuits embodying the selective stop motion control devices;

Figure 25 is a detail view in side elevation of a thread tensioning device employed with each thread stop motion device, a portion of the casing and other parts being broken away and shown in section; and

Figure 26 is a fragmentary detail view of the cooperating furnishing wheels, showing particularly the recessed radial blades between which the main thread passes as the furnishing wheels rotate to draw the thread from the bobbin and advance the same to the regular stitch wheel or sinker which feeds the thread into the needles.

Like reference characters designate corresponding parts in the several figures of the drawings, and certain parts will be recognized by those skilled in the art as being conventional, for which reason the same will not be described in detail.

Figures 1 and 2 together represent an assembly of a knitting machine having incorporated therein the novel features which constitute the present invention. As shown in these views, 1 generally designates a stationary bed plate which is supported at any desired elevation by legs 2 which normally rest upon the floor at the side of the machine. The bed plate is generally circular, and preferably extends radially outwardly beyond the legs 2 as indicated at 3, and adjacent to the outer margin thereof, the extension 3 is provided with a plurality of openings arranged in circumferentially spaced relation to each other. Each opening is preferably provided with a porcelain bushing mounted therein, forming a thread guide, as indicated at 4. The number of guides 4 provided in the extension 3 may be greater than the number actually receiving a thread at any one time, according to the particular setup for a given type of fabric to be knitted, and in arranging the guides 4 at intervals around the margin of the bed plate, those guides may be employed which are most conveniently located for the selected setup of thread

feeds which may be varied from time to time for various stitch patterns. At the center of the bed plate 1, the bed plate is provided with a substantially thickened section as indicated at 5, the section 5 being circular and forming a central hub about which a brake drum 6 extends for free rotation thereabout. The brake drum 6 is provided at its lower side near the outer margin thereof with gear teeth 7 adapted to mesh with the teeth of a drive gear 8 fixed on a drive shaft 9 which is suitably journaled in bearings 10 and 11 respectively attached to the lower side of the bed plate 1 and an extension plate 1' which is in turn attached to the upper side of the bed plate as by means of bolts 12 so as to extend towards one side of the machine. The drive shaft 9 may be driven from any convenient source of power. By way of illustration herein, the power source is shown as an electric motor 13 connected by V belts 14 to the drive shaft 9 through the intermediary of a free wheeling clutch generally designated 15, mounted on the outer end of the drive shaft 9 in alignment with the drive pulley 16 on the motor shaft 17. It is to be understood that my invention is not intended to be limited to the drive just described, since this is optional and may be varied as desired.

Fixed to the upper side of the central hub 5 which forms a part of the bed plate 1, is a hollow sleeve 18, said sleeve being held stationary on the bed plate and serving as a vertical guide or axle on which an elongated hub 19 of the needle cylinder 20 is mounted for rotation thereabout. The lower extremity of the needle cylinder hub 19 is keyed to a collar 21 having a radial flange 22 provided with a notch 23 which in turn receives an upstanding lug or boss 24 on the upper side of the brake drum 6. Thus, rotation imparted to the brake drum 6 is transmitted through engagement of the lug 24 in the notch 23 to the collar 21, and the rotation is in turn imparted by the collar 21 to the needle cylinder hub 19 and consequently to the needle cylinder 20. 25 designates a key and 26 a set screw for restraining the key against accidental displacement, thereby insuring a positive driving relation between the collar 21 and the hub 19.

Mounted around the needle cylinder 20 is a ring of spring needles 27. The needles are preferably removably attached to the needle cylinder by conventional caps and leathers 28 and associated cap bolts 29. As the fabric is knitted on the needles 27, it is taken up in an upward direction by suitable take-up mechanism generally designated 30. Between the needles 27 and the take-up mechanism 30, the fabric, designated F, is preferably passed through a cloth ring 31 which aids in equally distributing the tension about the fabric in a manner more particularly disclosed in my prior Patent No. 2,081,816 granted May 25, 1937. This cloth ring may be supported in any suitable manner, but preferably by means of a stand 31' connected at its lower end to a slotted arm 31'' attached to the bed plate 1. Positioned above the cloth ring 31 and fixed to a vertical shaft 32 is a main spreader 33 and an auxiliary spreader 34 about which the cloth F passes before it reaches the friction rolls 35, 36 and the cloth roll 37 which form parts of the take-up mechanism 30. The main spreader 33 extends upwardly between a pair of horizontally spaced bars 38, 38 arranged below the knitted fabric F. friction rolls 35, 36, and as the knitted fabric F is drawn upwardly from the main spreader 33 to the friction rolls 35, 36, the fabric passes be-

tween the bars 38, 38 in the conventional manner. Leathers 39 attached to brackets 40 adjustably mounted on the bars 38, 38 protect the fabric from undue rubbing against the bars as the fabric passes therebetween.

10 The vertical shaft 32 is journalled in the sleeve 18 and extends through an opening in the center of the bed plate aligned with the central opening in the sleeve. Fixed to the lower end of the shaft 32 is a gear 41, the teeth of which mesh with a second drive gear 42 fixed on the inner end of the drive shaft 9. Accordingly, a drive is established from the motor 13, through the drive shaft 9 and gears 41, 42 to the vertical shaft 32, causing the shaft 32 to be rotated in the same direction and at the same speed as the needle cylinder 20. The rotary movement of the vertical shaft 32 is transmitted to the take-up mechanism 30 by means of the main spreader 33, as will be obvious from the illustration in Figure 1. A gear housing or casing 41' is preferably attached to the lower side of the bed plate 1 to enclose the various drive gears.

25 The take-up mechanism 30 is attached at its upper end to a short vertical shaft 43 mounted for rotation in a bearing plate 44, the bearing plate in turn being fixed to an overhanging arm 45 as by means of bolts 46. The overhanging arm 45 is extended from a vertical post or column 30 47 which is fixed by bolts 48 at its lower end to the extension plate 1' which extends to one side of the bed plate 1. Hangers 49, 49 engaging eyes 50, 51 respectively provided at the upper side of the overhanging arm 45 and bearing plate 44, 35 may be utilized to support a substantial part of the weight of the take-up mechanism from the ceiling at the site of the machine.

30 Disposed on a reduced portion 44' of the hub 44" on the lower side of the bearing plate 44, and keyed thereto by a key 52, is a bevel gear 53 which is adapted to engage corresponding bevel gears 54, 54 which form a part of ratchet instrumentalities generally designated 55, 55 which actuate the rolls of the take-up mechanism responsive to rotary movement of the take-up mechanism respecting the vertical axis of the knitting machine. A nut 56 threaded on the lower end of the shaft 43 serves to hold the bevel gear 53 in its fixed position above referred to, and 50 also serves to restrain the key 52 against accidental displacement.

35 In suspending the take-up mechanism 30 on the lower end of the shaft 43, the attachment is so made that the shaft 43 will rotate about its vertical axis corresponding to the rotation of the take-up mechanism about the axis of the vertical shaft 32. Attached to the upper end of the shaft 43 so as to be rotatable therewith, is a brake drum 57. Extending about the brake drum 60 57 is a pair of brake bands 58, 59. One end of each of the bands 58, 59 is anchored by a bolt 60 to the bearing plate 44, and the free ends of the respective bands 58, 59 carry a pair of pins or studs 61, 62 engaged by the respective links 63, 64. The ends of the links 63, 64 opposite to the respective pins 61, 62 are pivotally connected at diametrically opposite points to a brake actuator plate 65 fixed to the end of a rock shaft 66 terminating near the free ends of the brake bands 70 58, 59. The rock shaft 66 is mounted in spaced bearing brackets 67, 68 attached to the upper side of the overhanging arm 45 which extends from the upper end of the vertical column or post 47. Connected to the end of the rock shaft 66 opposite to the brake actuator plate 65 is a crank 75

arm 69, the attachment being made in any suitable manner such as by means of the clamp bolt 79. Pivotally connected to the free end of the crank arm 69 is a brake rod 71 which extends downwardly therefrom in the vicinity of the column or post 47. The lower end of the brake rod 71 is preferably slotted as at 72 to receive a bolt 73 carried by a brake lever 74. Due to the slot 72, a limited lost motion is provided between the brake rod 71 and the brake lever 74 as will hereinafter be more fully apparent. An adjustable stop screw 75 extending through the crank arm 69 serves to limit rocking movement of the rock shaft 66 in one direction, as will be obvious from Figures 5 and 6.

The brake lever 74, as best seen in Figures 3 and 4 is preferably provided at one end with a handle 76 which may be conveniently grasped by the operator of the knitting machine while standing at a position near the side of the machine where the drive motor is located below the extension plate 1' to which the motor is attached by hangers 77 threaded into the extension plate 1' at their upper ends and passing through the base of the motor at their lower ends. The opposite end of the brake lever 74 is suitably fixed to the outer end of a second rock shaft 78, the attachment being made in any suitable manner, as by means of the clamp bolt 79. The rock shaft 78 is mounted in spaced bearing brackets 80, 81 disposed at the upper side of the bed plate 1 and extension plate 1', so as to be free to rock in opposite directions. The end of the rock shaft opposite to the brake lever 74 has fixed thereto a crank arm 82, the attachment of which may be made in a manner similar to that of the brake lever through means of a clamp bolt 83. The free end of the crank arm 82 is pivotally connected to one end of a short link 84, and the opposite end of the link 84 is pivotally connected to the free end of another crank arm 85 fixed to the end of a short rock shaft 86 as by means of the clamp bolt 87. The short rock shaft 86 is journaled in a bearing block 88 mounted on the bed plate 1, and the end of the shaft 86 carries an actuator plate 89 similar to actuator plate 65. The actuator plate 89 is fixed on the shaft 86 to rotate therewith, and has pivotally connected thereto at diametrically opposite points brake links 90, 91. The opposite ends of the links 90, 91 are respectively pivotally connected to the free ends of a pair of brake bands 92, 93 disposed about the brake drum 6, the connection between the links and the brake bands being preferably made by screws 94, 95 as best shown in Figures 3 and 4. The brake bands 92, 93 are anchored at their ends opposite to the ends connected to the links 90, 91, the anchorage being made by a bolt 96 extending through the bed plate 1 as shown in Figure 2. A coil spring 87 is connected at one end to the brake lever 74, as shown at 98 in Figures 3 and 4, and the other end of the coil spring is attached to a bracket 99 clamped to one of the hangers 77 as best seen in Figure 2. The tension of the coil spring 87 normally serves to urge the brake lever 74 in a downward direction at the end adapted to be actuated by the operator, and when it assumes this downward position, both sets of brakes hereinbefore described are normally applied, the upper brake being the take-up mechanism brake, and the lower brake being the needle cylinder brake.

When the knitting machine is in operation the brakes are normally released and when the power

drive is interrupted the brakes are applied. To start the operation of the machine, the brakes are first released by lifting the brake lever 74 in an upward direction through the aid of the operating handle 76, this lifting operation causing the lower rock shaft 78 and the various levers and links associated therewith to be actuated to release the brake bands 92, 93 from braking engagement respecting the needle cylinder brake drum 6. In lifting the brake lever 74 in an upward direction, upward movement is imparted to the brake rod 71, which in turn causes the upper rock shaft 86 to be rocked in one direction to release the brake bands 58, 59 from braking engagement respecting the take-up mechanism brake drum 57. A limited lost motion is provided at the connection between the brake rod 71 and the brake lever 74 so as to compensate for unequal adjustment or wear of the brake bands associated with the respective brake drums and the brake band actuating instrumentalities, this lost motion being afforded by the slot 72 through which the connecting bolt 73 extends at the lower end of the brake rod 71.

In order to hold the brakes in a released condition against the yieldable action of the coil spring 97 which normally tends to urge the brake lever 74 downwardly and thereby apply the brakes, a trip or trigger device is provided as best shown in Figures 3, 8 and 9. The trip device includes a short rock shaft 100 rotatably mounted in a block 101 which is attached to the extension plate 1' as by means of screws 102 adjacent to the brake lever 74. Fixed to one end of the rock shaft 100 is an arm 103 which extends generally upwardly therefrom to present an abutment surface 103' at its upper extremity, adapted to engage beneath an abutment pin 104 fixed to the brake lever 74 and projecting from one side of the latter as shown in Figure 3. At an intermediate point in the length of the rock shaft 100, a pin 105 is fixed thereto and extends in an upward direction therefrom, generally parallel to the arm 103. The block 101 is suitably recessed at 106 to receive a coil spring 107 having one end seated in the base of the recess 106, and its other end disposed in abutting relation to the pin 105, as shown in Figure 8. The spring 107 is normally under sufficient compression to exert pressure upon the pin 105 to rock the shaft 100 in a counter-clockwise direction as viewed in Figure 8, thereby normally disposing the upper end of the arm 103 in the position shown in Figure 4, with the abutting surface 103' of the arm 103 disposed below the pin 104 on the brake lever 74. When so positioned the arm 103 will positively maintain the brake lever 74 in an elevated position, holding the brakes released. Lifting of the brake lever 74 in an upward direction to a position in which the pin 104 is elevated above the upper end of the arm 103, automatically allows the arm 103 to move beneath the pin 104 under the influence of the spring 107 acting upon the pin 105 fixed to the rock shaft 100. To displace the arm 103 from beneath the abutment pin 104, an automatic trip is provided on the rock shaft 100 to be actuated by the main power control 108, shown generally in Figures 3 and 4 and in detail in Figures 10 to 13. The main power control includes a pull rod 109 which extends through and is slidably mounted in the housing 110 of the main power control unit 108, said housing being provided with a removable cover 111. The pull rod 109 is provided with an operating handle 112 which is positioned adjacent to the brake

lever 74 to enable the operator of the machine to conveniently operate the brake lever 74 with one hand and the main power control with the other hand. The main power control is connected to suitable electric circuits which in turn control operation of the motor 13 in a manner hereinafter more specifically described. To close the power circuit to start the motor 13, the pull rod 109 is pulled towards the operator when standing in front of the handle 112, and in interrupting the power circuit to stop the machine, the pull rod 109 moves in the opposite direction under the influence of a coil spring 113 disposed within the control unit housing 110 and encircling the pull rod 109 as later described.

Adjustably fixed on the pull rod 109 by means of a set screw 114 is a collar 115 carrying a pin 116 which is disposed somewhat above the rock shaft 100 in the block 101 and at the side of the latter opposite to the arm 103. Fixed to the end of the rock shaft 100 opposite to the arm 103, and rockable with the shaft 100 is a generally upright arm 117. The upper end of this arm 117 is slotted or milled out to a substantial depth as at 118, and pivotally mounted in the slot is a trigger 119 having an inclined upper edge as at 120. The trigger 119 is pivotally connected to the arm 117 by means of a pin 121 extending across the slot 118. Seated in a recess 122 in the arm 117 at one side of the pivot pin 121 is a coil spring 123 having its upper end engaged beneath the forward end of the trigger 119 as best shown in Figure 9. In the normally expanded condition of the coil spring 123, the trigger 119 assumes a somewhat elevated position at its forward end, disposing the trigger in the path of the pin 116 carried by the pull rod 109. During forward movement of the pull rod 109 in the operation of the main power control 108 to close the power circuit to the motor 13, the pin 116 engages the inclined upper edge 120 of the trigger member 119 as the pull rod approaches the limit of its outward movement, and as the pull rod continues to move forwardly, the pin 116 rides across the inclined edge 120, and progressively depresses the trigger 119 while the arm 117 is held in its upright position by the action of the spring 107 on the pin 105. Movement of the arm 117 beyond this upright position is prevented by a stop pin 124 carried by the block 101 and projecting to one side thereof. When the arm 117 comes into engagement with the abutment pin 124, and further movement of the arm is arrested, the arm 103 on the opposite end of the rock shaft 100 will be disposed beneath the pin 104 on the brake lever 74 which has been initially raised before the pull rod 109 is pulled outwardly. As the pull rod continues to approach its limit of outward movement, the pin 116 carried thereby passes off of the trigger 119, and the trigger rocks upwardly to its normal position shown in full lines in Figures 8 and 9 with its forward edge disposed behind the pin 116. Suitable trip means are provided to hold the pull rod 109 in its outward position just described until such time as the trip means are actuated to release the pull rod and cause the power circuit to be broken through action of the coil spring 113 which normally tends to urge the pull rod 109 in a rearward direction as viewed from the operating handle end of the pull rod represented at 112. The details of the main power control 108 and the trip means above referred to will be later described, and for the purpose of continuing the explanation of the operation of the trigger 119, it will be assumed at

this point of the explanation that the trip means have been suitably actuated to release the main power control to cause interruption of the motor drive. When the main power control is released the pull rod 109 moves rearwardly under the influence of the spring 113, carrying with it the pin 116. Rearward movement of the pin 116 thereupon imparts rearward rocking movement to the arm 117 through engagement with the trigger 119, as viewed in Figures 8 and 9, until the pin 116 passes by the trigger 119 as the pull rod 109 continues to move rearwardly to the position shown in Figures 10 and 11. In rocking the arm 117 in a rearward direction, corresponding rocking movement is imparted to the shaft 100, and consequently to the arm 103 which is forcibly displaced from beneath the pin 104 on the brake lever 74 by the pressure of the spring 113 on the pull rod 109. As the upper end of the arm 103 becomes disengaged from the pin 104, the brake lever 74 automatically moves downwardly under the influence of the spring 97 which causes the brakes to be applied substantially instantaneously with the interruption of the power drive, as hereinbefore described. The brakes remain applied until such time as operation of the knitting machine is resumed, whereupon the brakes are first released by operation of the brake lever 74, and the pull rod 109 is then pulled forwardly to close the power circuit which simultaneously resets the brake trip device or holding means to hold the brakes released as already described in the explanation of the parts 100 to 104 etc., and 114 to 123.

More particularly describing the main power control 108, and referring particularly to Figures 10 to 13 inclusive, 125 designates a crosshead which is fixed to the pull rod 109 within the housing 110, as by means of a pin 126, the crosshead being movable forwardly and rearwardly with the pull rod 109 within the housing. The crosshead is laterally extended towards one side of the housing 110 and slidably engages a guide bar 127 fixed in the housing and arranged generally parallel to the pull rod 109. Attached to the upper side of the crosshead, as by means of screws 128 is a plate 129 which is extended forwardly above the pull rod 109, with sufficient clearance therebetween as not to interfere with the spring 113. The plate 129 serves as a support for a knife switch blade 130 which is attached to the forward end of the plate 129 as by means of a laterally offset arm 131 provided at the upper end of the switch blade 130. The arm 131, and consequently the switch blade 130, are preferably insulated from the support 129 through provision of an insulating strip 132 interposed between the arm 131 and the support 129, and suitable insulating bushings surrounding fasteners 133.

Mounted on the forward wall of the housing 110 near one lower corner thereof is an insulating block 134 which is preferably attached to the wall by screws 135. Attached to the insulating block 134 as by means of screws 136 is a pair of fixed switch contacts 137 arranged in vertically spaced relation to each other, each switch contact having closely spaced spring jaws to receive the switch blade 130 therebetween when the pull rod 109 is pulled forwardly to its operative power circuit closing position hereinbefore described. The contacts 137 are connected by conductors 138 and 139 in a power circuit shown in the circuit diagram of Figure 24 which will hereinafter be described in more detail,

However, it should be understood at this point that when the switch blade 130 is moved to the broken line position shown in Figures 10 and 11, the contacts 137 will be bridged by the switch blade to close the power circuit, and when the switch blade 130 is disengaged from the contacts 137, the power circuit will be broken and operation of the driving motor 13 will be discontinued through the interruption of the power supplied thereto under the control of the main control unit 108.

Extending forwardly from the crosshead 125 is a pair of laterally spaced ears or bosses 140 between which is mounted a dog 141 which is pivotally connected to the spaced ears 140 by a pin 142. A U-shaped spring member 143 extending about the pin 142 and having one arm extended into a recess 144 in the lower side of the crosshead 125, and its other arm arranged in abutting relation to the upper side of the dog 141, normally serves to urge the dog in a downward direction, that is in a clockwise direction about the axis of the pivot pin 142, as viewed in Figure 12. The dog is provided with an abrupt shoulder 145 which is adapted to coact with a trip latch 146 forming a part of a magnetically controlled latch unit generally designated 147. The magnetic latch unit is mounted in the lower part of the housing 110, and includes a base plate 148 supported on posts 149 extending upwardly from the bottom of the housing 110, and to which the base plate 148 is attached as by screws 150. At one side of the base plate 148 an elongated side frame 151 is provided, and a shorter side frame 152 extends upwardly from the opposite side of the base plate. Between the side frames 151 and 152 is rockably mounted a member 153 having a radially extended arm 154 arranged above and towards one side of the base plate 148. Coacting with the free end of the arm 154 is an armature 155 which is mounted to rock in a vertical plane about a horizontal axis, the armature being pivotally attached at its lower edge by a pintle 156 extending through the side frame 151 at one end, and through a supplemental support 157 at the other end. A magnet 158 is arranged in cooperative relation to the armature 155, the same being preferably fixed to an upright support 159 at one end of the base plate as shown in Figures 12 and 13. A light leaf spring 160 attached to the armature 155 and having abutting engagement with the magnet 158, normally tends to rock the armature 155 in a clockwise direction as viewed in Figure 12, when the magnet 158 is not energized. The armature 155 is provided with an extension 155' at one end which is normally adapted to move beneath the free end of the arm 154 to hold the latter arm in an elevated position as shown in Figures 12 and 13. Below the arm 154 and extending from the body of the part 153 as a part thereof is an abutment tail 161 adapted to cooperate with an adjustable stop screw 162 mounted on the base plate 148, and serving to limit the pivotal movement of the arm 154 in a clockwise direction as viewed in Figure 12. The adjustment of the stop screw 162 should be such that the free end of the arm 154 may be rocked upwardly sufficiently far to allow the extension 155' of the armature 155 to move beneath the arm, but not substantially farther.

The body of the part 153 intermediate its opposite ends is provided with a curved face 163 which is adapted to cooperate with the tail 161 on the pivotal trip latch 146 which is mounted between spaced supports 165, 165. 168 represents

a pin which serves to pivotally connect the trip latch 146 to the supports 165, 165. A coil spring 167 having one end extended at 168 for engagement with an abutment 169 on the base plate 148, and its other end extended at 170 for abutting engagement with the lower side of the tail 164 of the trip latch 146, normally serves to urge the trip latch 146 in a counter-clockwise direction, as viewed in Figure 12. The same spring pressure acting upon the trip latch 146 is transmitted through the tail 164 of the trip latch to a shoulder 171 provided at the upper end of the curved face 163 on the part 153, thereby tending to normally rock the part 153 and its extended arm 154 in a clockwise direction. The radius of the curved face 163 is so selected that when the free end of the arm 154 overlies the extension 155' on the armature 155, the tail 164 of the trip latch 146 is positively restrained against movement in a clockwise direction as viewed in Figure 12. In other words, under these conditions, the center of curvature of the face 163 is at this time eccentric to the pivotal axis of the trip latch 146, and the distance between the pivotal axis 20 of the trip latch and every point of the curved face 163 below the position of the tail of the latch 146 in Figure 12, is too small to allow the tail of the trip latch to move downwardly. Consequently, so long as the arm 154 is restrained against downward movement by the armature extension 155', the trip latch 146 will be positively held in the position shown in full lines in Figure 12. Thus with the dog 141 moved to its dotted line position shown in Figure 12, with the shoulder 145 engaged with the trip latch 146, which occurs when the pull rod 109 of the main control unit is pulled out to close the power circuit, the pull rod will be held out in its operative position, compressing the spring 143 between 30 the forward side of the crosshead 125 and the forward wall of the casing 110. It will be understood that as the pull rod 109 is pulled forwardly, the dog 141 will rock slightly in a counter-clockwise direction as permitted by the yieldable action of the spring 143, while the dog passes the trip latch 146, until the shoulder 145 of the dog reaches the position in advance of the trip latch as shown in dotted lines in Figure 12.

In order to trip the main power control to allow 50 the same to be restored to its rearward, inoperative position constituting the power interrupted position, the magnet 158 must be energized. This may be accomplished by various 55 selective auxiliary controls and auxiliary control circuits shown in the circuit diagram of Figure 24, said auxiliary controls preferably including a manually operable stop button or switch generally designated 172, a thread responsive stop motion device generally designated 173, and a 60 fabric stop motion device generally designated 174. Before discussing the details of these auxiliary control devices and circuits which will hereinafter be more specifically described, it may be assumed that the circuit in which the magnet 65 158 is connected may be selectively energized by any one of the auxiliary control devices independently of the others. When so energized the magnet serves to attract the armature 155 against the pressure of the leaf spring 160, causing the armature 155 to be rocked about its pivotal axis 156 in a counter-clockwise direction as viewed in Figure 12, thereby withdrawing the armature extension 155' from beneath the free end of the arm 154. Thereupon, the force stored 70 75 in the spring 143 which was compressed by the

outward pull of the pull rod 109 to close the power circuit, will be exerted against the cross-head 125 fixed to the pull rod 109 to urge the pull rod 109 in a rearward direction. This causes the dog 141 to be carried rearwardly with the pull rod 109 from its dotted line position shown in Figure 12 to the full line position shown in that figure, and the force of the spring 113 is exerted through the dog 141 against the trip latch 146 to cause the trip latch 146 and the tail 164 thereof to move in a clockwise direction as viewed in Figure 12. As the tail 164 of the trip latch 146 moves downwardly, the member 153 having the curved face 163 will be caused to rock in a counter-clockwise direction as viewed in Figure 12, during which movement the curved face 163 will occupy such positions as to afford free downward movement of the tail 164. It will be obvious that the force of the spring 113 is considerably greater than that offered by the spring 167 which latter spring normally tends to resist clockwise movement of the trip latch 146 and its tail 164, as viewed in Figure 12. When the dog 141 has passed by the trip latch 146 in its rearward movement with the pull rod 109 as just described, the spring 167 will restore the trip latch 146 and its associated cooperating parts 153, 154 to their respective positions shown in full lines in Figure 12, thereby allowing the armature extension 155' to move beneath the free end of the arm 154 and again lock the trip latch 146 in an operative position ready to reengage the dog 141 upon further actuation of the pull rod 109 to its operative position previously described.

Before describing the selective auxiliary control circuits and stop motions 172, 173 and 174, reference will be now made to a typical setup of thread feeds which may be employed with a machine of this character, and having particular regard for Figures 1, 2 and 23. Extending in concentric circles about the legs 2 of the machine near the lower ends thereof is a pair of radially spaced bars 175 which are arranged in a common plane and supported by brackets 176 suitably attached to the legs 2. These bars serve to support bobbins 177 from which the threads are directed to the needles 27 on the needle cylinder 20. The bobbin may be adjusted to any desired point on the supporting bars 175, and there may be employed as many bobbins as necessary to incorporate the desired number of threads in the knitted fabric at one or more feed stations, only one of which is illustrated in the drawings. For example, from bobbin 177 shown in Figure 2, the main thread T is directed upwardly to the thread stop motion 173 and then to an intermediate tensioning device 178, both later described, the tensioning device 178 being attached to a supporting plate 179 fixed by a set screw 180 to the upper end of a central standard 181 lying on the central axis of the machine below the bed plate 1. The lower end of the standard 181 is attached by clamping nuts 182, 182 to the intersection of the cross bars 183, 183 attached at their outer ends to the legs 2 of the machine and with each cross bar extending between diagonally opposed legs where four legs are provided. From the tensioning device 178, the thread T extends upwardly through the guide 4 in the outer edge of the bed plate extension 3, and thence upwardly to a guide arm 184 suitably attached to a convenient fixed point outside of and relatively near the needle circle. The thread then passes through a porcelain guide 185 carried by the

free end of the guide arm 184, and then through a pointed metal guide 186 disposed at one side of the guide 185 and carried by an auxiliary arm 184' which is attached to the arm 184 by rivets 187. From the pointed guide 186, the thread extends between a pair of wheels 188, 189 arranged for rotation about vertical axes outside of the needle circle. Each of these wheels 188, 189 is provided with circumferentially spaced radial blades, with the blades of one wheel overlapping between adjacent blades of the other wheel. The extreme outer edges of the blades are preferably provided with shallow recesses through which the thread T runs in passing between the wheels as shown in Figures 23 and 26, the recesses serving to keep the thread between the wheels and preventing the thread from becoming displaced in an upward or downward direction. One of the wheels, for example 188, is positively rotated through provision of a gear 190 operatively connected thereto and meshing with the shanks of the needles 27 at a point below the spring beards of the needles, that is, just above the needle caps 28. The other wheel 189 is carried by a supporting arm 191 which is preferably yieldably urged towards the cooperating wheel 188 by any suitable means generally designated 192, the details of which are immaterial herein and are well known to those skilled in the art. The arm 191 is adjustably mounted on a vertical stand 193 attached at its lower end to a slotted link 194, which in turn is adjustably connected to a slotted stand supporting ring 195 mounted on the upper side of the bed plate 1.

It will be understood that as the wheels 188, 189 are rotated by the drive established with the needles 27 by the gear 190, the wheels will draw the thread T uniformly from the bobbin 177, keeping the thread taut between the wheels and the bobbin and normally under uniform tension. For this reason, the wheels 188, 189 will be hereinafter termed furnishing wheels.

From the furnishing wheels, the thread T passes through a guide 196 in another guide arm 197 suitably positioned outside of the needle circle, and then through another guide 198 in the free end of the guide arm 197, from which the thread is directed to a stitch wheel or sinker 199, likewise mounted in any convenient manner at the outside of the needle circle, as by means of a suitable stand. The stitch wheel or sinker 199 feeds the thread T under the beards of the needles 27 as the needles progressively move past the stitch wheel during rotation of the needle cylinder 20, in a well known manner. At the time the thread is fed under the needle beards, the fabric is pushed down by a shoe or equivalent cloth push down means generally designated 200 which may be adjustably supported by the cloth ring 31 located above the needle cylinder and carried by arms 201 and 202 which are in turn connected to stands 31' and the bracket 203 on the post or column 41. If desired, a backing thread B may be presented to the needles in a conventional manner in advance of the main thread feed represented by the thread T. The use of a backing thread and the manner of incorporating the same in the fabric is well known and need not be described in detail herein. 204 represents in Figure 23 a guide arm having a guide 205 provided at the free end thereof for directing the backing thread 75 B to a backing wheel 206. Between the backing

wheel 205 and the stitch wheel or sinker 199 is a clearing wheel 197.

After the backing thread B and the main thread T have been presented to the needles, the needles move past a presser 206 which presses the needle beards closed. A lander burr or wheel 209 position within the needle circle then lands the old stitches or thread loops on the needle beards, and as the needles continue to move past the lander wheel 209, a cast off burr or wheel 210 casts off the old stitches, thereby forming new stitches or thread loops constituted by the feeding of the main thread T under the needle beards. The lander wheel 209 and cast off wheel 210 may be conveniently supported by arms 211 carried by an inside supporting ring 212 having a hub collar 213 engaging over the upper end of the central sleeve 18 and secured thereto by a set screw 214.

It will be understood that the backing thread B would normally be supplied from another bobbin corresponding to bobbin 177 in Figure 2, and additional thread feeds may be duplicated at other stations about the machine, as desired, in the well known manner.

With the foregoing general description of the knitting operation in mind, reference will now be made to the auxiliary control circuits and stop motions hereinbefore referred to.

Considering first the thread stop motion shown in detail in Figures 14 to 16 inclusive, 215 designates a casing which is preferably provided with a removable side wall 216. Extending through the opposite side walls of the casing and journalled therein is a pin 217 having at one end thereof a radially upwardly offset arm 218 which carries at its upper end a cross bar 219. Mounted on the respective opposite ends of the cross bar 219 and extending upwardly therefrom is a pair of porcelain members 220, each being provided with a U-shaped recess 221 in which the thread T is adapted to be disposed as it comes from the bobbin 177 as clearly shown in Figure 2. Fixed to the pin 217 and disposed within the casing 215 is a block 222, and attached to the block and extending downwardly therefrom is a relatively stiff wire or blade 223 which forms a movable electrical contact which is grounded to the frame of the knitting machine through the casing 215. The movable contact 223 is adapted to cooperate with a fixed contact 224 suitably attached to the side of the casing 215 opposite to the side wall 216, said fixed contact having a yieldable spring blade 225 disposed for engagement with the movable contact 223 when the latter is rocked to its dotted line position shown in Figure 14. A light coil spring 226 having one end engaged with the movable contact 223 and its other end fixed to an adjustable square nut 227 mounted on an adjusting screw 228 normally urges the movable contact 223 and the porcelain arms 220 to their full line positions shown in Figure 14, while allowing the arms and the contact 223 to be rocked to their dotted line positions shown in Figure 14 when tension on the thread T exceeds a predetermined amount, as determined by the setting of the adjusting screw 228. A fixed abutment 229 extending upwardly from the upper side of the casing 215 at one edge thereof serves to engage the cross bar 219 to limit movement of the porcelain arms 220 in a counter-clockwise direction as viewed in Figure 14, beyond the position illustrated in full lines in that figure.

Also journalled in the opposite side walls of the casing 215 is a second pin 230. This second pin 230 is downwardly offset at one side as at 234 and carries an adjustable counterweight 232 which is threadedly received thereon. Fixed to the pin 230 near the upper end of the offset arm 231, and extending upwardly therefrom is a wire arm 233 which is reversely bent at its upper end as at 234 to form a second arm laterally spaced from the arm 233. The lower end of the arm 234 is offset at 235 at a point slightly above the base of the recesses 221 in the porcelain arms 220. Fixed to the pin 230 and disposed within the casing 215 is a block 236 constituting a second movable electrical contact which is adapted to cooperate with a second spring blade 237 forming a part of the fixed contact member 224. When the thread T is disposed in the porcelain arms 220, the wire arms 233, 234 normally lie to the right of the thread as shown in Figure 14, with the thread extending between the spaced porcelain arms 220 and above the offset 235 as shown in Figure 15. In such position of the wire arms 233, 234, as represented in full lines in Figure 14, the contact block 236 on the pin 230 is normally out of engagement respecting the fixed contact blade 231, and the counterweight is rocked to an inclined position to the left of the vertical as viewed in Figure 14. Should the thread T break under such circumstances, the wire arms 233, 234 will be released and the pull of the counterweight 232 will cause the arms to rock in a counter-clockwise direction as viewed in Figure 14, causing the movable contact block 236 to engage the fixed contact blade 231. It will be accordingly seen that both the porcelain arms 220, 220 and the wire arms 233, 234 are controlled by the thread T, the former being responsive to tension on the thread, and the latter being responsive to the breaking of the thread.

Mounted at one end of the casing 215 and extending upwardly therefrom are laterally spaced guard arms 238, 238 and an intermediate guard plate 239, the latter lying about on a vertical center of the stop motion device 173, and the arms 238, 238 being sufficiently spaced therefrom as to afford clearance that the same will not interfere with either the porcelain arms 220, 220 or the wire arms 233, 234, as will be seen from Figures 15 and 16. The purpose of the guard arms 238, 238 and plate 239 is to prevent the thread T from becoming inadvertently displaced from the recesses 221 in the porcelain arms 220 when the porcelain arms have been rocked to the limit of their movement produced by the spring 226 in case of a break in the thread T or displacement of the thread from its normal engaged position with respect to the tensioning device 173 which produces a substantial slack in the thread on displacement from the latter device.

An insulated electrical terminal 240 operatively connected with the fixed contact member 224 within the casing 125 is disposed on the outside of the casing at one side for connection of the stop motion device 173 to the electrical control circuit shown in Figure 24. As many of these stop motion devices are provided as there are thread feeds, and the devices are preferably mounted on a support 241 extending about the legs 2 of the machine at a position just above the bobbins 177. As shown in Figure 2, this support 241 has the form of a circular metal band attached to the legs 2 by hangers 242. Ad-

justment of the elevation of the support 241 may be accomplished by means of the U bolts 243. The lower edge of the support 241 is preferably flanged as at 244 to provide a short horizontal ledge extending radially inwardly therefrom, and attached above this ledge by means of screws 245 is a block 246 to which an extension 247 on the base of the stop motion device 173 is attached by means of a screw 248. When so mounted as just described, the stop motion device 173 extends generally radially inwardly from the support 241, as clearly shown in Figure 17. Associated with each of the stop motion devices 173, and positioned in proximity thereto is a slab catcher generally designated 249, shown best in Figures 17 to 19 inclusive. The slab catcher includes an inclined bracket 250 having an offset 251 at one end for attachment to the block 246 by means of a screw 252. At the other end of the bracket 250 is an oppositely disposed offset 253 to which is attached a U-shaped frame 254. The lower arm 255 of the frame is fixed to the offset 253 by a bolt 256 and clamping nut 257. The head of the bolt is disposed between the arms of the frame 254 and includes a circular body 258 on which is disposed a disc 259 provided with circumferentially spaced openings 260 of various sizes. The disc 259 preferably has a snug fit on the circular body 258, but is adjustable rotatively about the axis of the body to selectively position the openings 260 in register with the vertically spaced porcelain thread guides 261, 262. The lower guide 261 is adjustably mounted in a slot 263 in the lower arm 255 of the frame 254, and the upper guide 262 is adjustably mounted in a corresponding slot 264 in the upper arm 265 of the frame. The thread T leads directly from the bobbin 177 and thence upwardly through the porcelain guides 261, 262 and one of the openings 260 in the intermediate disc 259, the proper opening 260 being selected in accordance with the size of the thread. From the upper guide 262, the thread extends directly to the stop motion device 173 which is positioned relatively close thereto as illustrated in Figures 17 and 18.

Between the stop motion device and the guide 4 in the bed plate extension 3, the thread T engages the tensioning device 178 as shown in Figure 2. The details of this tensioning device are best illustrated in Figure 25, wherein 266 denotes a casing preferably provided with a removable side wall. Journalled in the opposite side walls of the casing 266 is a pin 267 having an upwardly extending arm 268 provided at one end thereof, and carrying at its upper extremity a cross bar 269, to the opposite end of which is attached a porcelain 270 having a recess 271 therein, generally similar to the porcelains 220. Fixed to the pin 267 within the casing 266 is a block 272 to which is attached one end of a coil spring 273 the opposite end of the coil spring being attached to an angular guide member 274 threadedly mounted on an adjusting screw 275. Tension of the spring 273 normally tends to urge the porcelain arm 270 in clockwise direction as viewed in Figure 25, the amount of movement of the arm being limited by a fixed abutment 276 extending upwardly from the upper side of the casing 266 and disposed for engagement with the cross bar 269. The tensioning device 178 is attached to its support 179 in any suitable manner, as by means of a screw 277 extending through an extension 278 on the base of the casing 266.

In the normal feeding of the thread T, the ten-

sioning device 178 is so adjusted as to impose only a very light tension upon the thread, or none at all if preferred, in which case the porcelain arm 270 will assume a position approximating that shown in Figure 25. Should the thread for any reason become unduly tensioned at some point between the bobbin 177 and the furnishing wheels 188, 189, the porcelain arm 270 will rock in a counter-clockwise direction as viewed in Figure 25, as permitted by the yielding of the spring 273, automatically causing the thread to become displaced from the recess 271 in the porcelain arm 270. The resulting slack in the thread will thereupon allow the wire arms 233, 234 of the stop motion device 173 to move under the influence of the counterweight 232 to the dotted line position shown in Figure 14, establishing contact between the movable contact member 236 and the fixed contact member 237 which in turn cause one of the selective control circuits to be operated to interrupt the power drive. Under some conditions, tension on the thread T may not be sufficient to cause the thread to become displaced from engagement with the porcelain arm 270 of the tensioning device 178, and in that event, the tension will cause the porcelain arms 220, 228 of the stop motion device 173 to rock in a clockwise direction as viewed in Figure 14, establishing contact between the movable contact member 223 and the fixed contact member 225 which also operate the control circuit to interrupt the power drive. In any case, however, the controls in one way or another will stop the machine before the thread T breaks under undue tension, and this is particularly the purpose afforded by the tensioning device 178 from which the thread may become displaced automatically under certain conditions, affording considerable slack in the thread so as to allow ample time to stop the machine before the slack is taken up. Should the thread become displaced from the tensioning device 178, it must be reengaged in the recess 271 of the porcelain arm 270 to reset the stop motion device 173 before the machine is restarted, as will be obvious.

Passing now to the fabric stop motion device illustrated in Figures 20 to 22 inclusive, 279 designates a vertically adjustable support which may be mounted at any convenient point on the outside of the machine in close proximity to the fabric F near the upper ends of the needles 27 on the needle cylinder 20. As shown, the support 279 may be carried by the cloth ring 31. Pivotedly attached to the lower end of the support 279 is an arm 280 which is free to rock on the axis of pins 281 extending thereinto at a point intermediate its opposite ends. Pivotedly attached to one end of the arm 280 is a dog 282 which is normally disposed in a generally upright position, with its lower extremity 283 tapered to approximately a point and disposed to ride on the outside of the fabric near the upper ends of the needles. The dog 282 is yieldably restrained against pivotal movement relative to the arm 280 by means of a detent 284 engaging in a notch 285 provided in the edge of the dog near its pivot 286. Additional notches may be provided in the dog if desired, to allow for adjustment of the dog to different positions other than the one shown in the drawings, which other positions require more or less force to rock the dog relative to the arm 280. A spring 287 disposed in the bore 288 extending through the arm 280, is interposed between the detent 284 and

an adjustable screw 289. Adjustment of the screw 289 in one direction or the other will increase or diminish the force necessary to be applied to the dog 282 to displace the recess 285 from engagement with the detent 284. Fixed to the end of the arm 280 opposite to the dog 282 is an electrical contact member 290 which extends upwardly therefrom and is disposed for engagement with one end 291 of an insulated electrical terminal 292 which is connected in one of the control circuits for controlling the automatic interruption of the power drive.

So long as the fabric being knitted is free of imperfections, the dog 282 will ride smoothly on the fabric, holding the arm 280 in the position shown in full lines in Figure 20, with the contact 290 spaced from the contact 29. Should a hole, drop stitch, needle run or other imperfection occur in the fabric, the point 283 of the dog 284 will drop into the same, and due to the rotary motion of the fabric, the dog will be forcibly rocked on its pivot 286 in a counterclockwise direction as viewed in Figures 20 and 22, displacing the notch 285 from engagement with the detent 284, and straightening out the dog in approximate alignment with the arm 280. When this occurs, the arm 280 will rock under the influence of a spring 280' in a clockwise direction as viewed in Figure 20, to the dotted line position illustrated in this view, thereby causing the contact 290 to move into engagement with the contact 291 in the direction of the arrow in Figure 22. The engagement of these contacts 290, 291 serves to operate the electrical control circuit. In any case where the fabric stop motion has been automatically operated to interrupt the driving power, the dog 282 must be reset to its full line position in Figures 20 and 21, before restarting the machine. In those cases where the fabric F is knitted to form a parting line, indicated generally at 293 in Figure 20 and which is customarily formed by omitting one or more needles from the needle cylinder, it is necessary to positively restrain the arm 280 against movement while the dog 282 is registered with the parting line during rotation of the fabric past the dog. For this purpose, the arm 280 may have adjustably fixed thereto an auxiliary arm or bar 294 which extends in a generally downward direction therefrom, with its lower extremity disposed for engagement with an abutment 295 attached to one of the needle caps 28 on the needle cylinder 20. Thus, as the fabric parting line 293 approaches the dog 282, the auxiliary arm 294 engages the abutment 295 and holds the arm 280 and dog 282 against movement about the pivot 281 in a clockwise direction, as viewed in Figure 20, until the parting line has passed beyond the dog, preventing the contacts 290, 291 from becoming engaged, and thus preventing operation of the fabric stop motion device as would otherwise occur.

Referring now to Figure 24 which represents a circuit diagram of the main power control circuit and associated auxiliary control circuits, it will be seen that 296 diagrammatically designates a plug which is adapted to be plugged into any convenient electrical outlet, preferably supplying A. C. power. From the plug 296 a conductor 297 leads to one terminal 298 of a double-pole single-throw switch 299. From the terminal 298, another conductor 300 leads to one side of the primary winding of a step-down transformer 301. The other side of the primary winding is connected by a conductor 302 to the opposite side of the plug 296, and also to the terminal 303 of the

switch 299. From terminal 304 of the switch 299 leads a conductor 305 which is connected to one side of the motor 13 which drives the machine, and this terminal 304 is also connected by a conductor 306 to one of two lamps 307, 308 which are shown arranged in series with each other, as interconnected by the conductor 309. From lamp 308 leads another conductor 310 which is connected to terminal 311 of the switch 299. While the lamps 307, 308 are illustrated in a series arrangement, this is not essential as they may be connected in parallel if preferred. As shown in Figure 2, the lamps are mounted within the circle of the fabric F, being suitably supported from any convenient fixed part of the machine, such as the central hub 213 of the inside ring 212. The purpose of the lamps is to facilitate inspection of the fabric by the operator of the machine, as afforded by the penetration of the light rays through the fabric.

To the side of the motor 13 opposite to that to which the conductor 305 is connected, the conductor 139 leading to one of the main power control contacts 137 is connected. The conductor 138 leading to the other main power control contact 137 is interconnected with the conductor 302 which leads to one side of the plug 296. Now when the blades 312, 312 of the switch 299 are actuated to close the switch and establish an operative connection between the respective pairs of terminals 298, 304 and 303, 311, the main power control switch represented by the contacts 137, 137 and switch blade 130, is conditioned for control of the motor 13. Thus when the pull rod 109 of the main power control unit 108 is pulled out or forwardly as hereinbefore described, causing the switch blade 130 to bridge the contacts 137, 137, the driving motor 13 will be energized and will remain energized by the holding engagement of the trip latch 146 respecting the dog 141 carried by the pull rod 109, as previously described.

It will be seen from the circuit diagram of Figure 24 that the primary winding of the step-down transformer 301 is always energized irrespective of the position of the switch 299, which latter switch is more or less of the character of a safety switch. Since the transformer 301 is of a relatively low powered type, the continuous energization of the primary winding does not involve any appreciable loss of power. Associated with the primary winding of the transformer is a secondary winding for stepping down the voltage from the normal 110 volts at the plug 296 to a relatively low voltage, preferably on the order of 18 volts. From one side of the secondary winding a conductor 313 leads to the several selective auxiliary control devices 172, 173 and 174, said conductor 313 being shown in the circuit diagram of Figure 24 interconnected with a conductor 314 extending to one side of the stop button 172, and interconnected with another conductor 315 leading to the insulated terminal 292 of the fabric stop motion device 174. Connection of the conductor 313 with the thread stop motion device 173 is made at the insulated terminal 240 on the latter. The opposite side of each of the control devices 172, 173 and 174 is grounded to the frame of the machine.

Leading from the opposite side of the secondary winding of the transformer 301 is a conductor 316 which is operatively connected to one side of the magnet winding 158 which forms a part of the main power control unit 108. The opposite side of the magnet winding 158 is con-

nected by a conductor 317 to a spring contact member 318 mounted upon a horizontal supporting plate 319 within the main power control unit housing 110. The supporting plate 319 is attached to and supported by lugs or bosses 320 disposed at the inner corners of the housing 110 and preferably formed integrally therewith, the plate being provided with a slot 321 through which the trip latch 146 projects in an upward direction for cooperation with the dog 141. The contact member 318 is preferably insulated from the supporting plate 319 by means of an insulating member 322.

Carried by the crosshead 125 on the pull rod 109 projecting forwardly therefrom is a contact pin 323 which is disposed for operative engagement with the spring contact 318 when the pull rod 109 is moved forwardly to close the power circuit at the contacts 137, 137. On engagement of the pin 323 with the contact member 318, the circuit in which the magnet winding 158 is included is grounded through the main control box which is connected to the frame of the knitting machine. This conditions the selective control circuits which include the auxiliary controls 172, 173 and 174 for selective energization of the magnet winding 158 by the auxiliary controls. That is to say, assuming that the machine is in operation, with the pull rod 109 moved outwardly to its operative position, the magnet 158 is not actually energized, but is conditioned to be energized by any one of the auxiliary controls 172, 173 and 174. Operation of the manual push button 172 causes one side of the secondary winding of the transformer 301 to be grounded, thereby completing the circuit through the magnet 158 which is also grounded at one side, thereby establishing a current flow through the magnet winding and actuating the armature 155 to release the trip latch 146 which in turn restores the pull rod 109 to its inoperative position, breaking the motor circuit at the contacts 137, 137 as hereinbefore described. A similar control of the energization of the magnet 158 is performed by automatic operation of the thread stop motion device 173 and the fabric stop motion device 174. In the case of the thread stop motion device, closing of the magnet circuit is accomplished either through the engagement of the movable contact member 223 with its associated fixed contact member 225 or through engagement of the movable contact member 236 with its associated fixed contact member 237.

Whenever the magnet 158 is energized and the pull rod 109 is tripped to its inoperative position causing interruption of the power drive, the pin 323 carried by the crosshead 125 on the pull rod 109 is automatically disengaged from the spring contact 318, thereby positively opening the magnet circuit so as to render the auxiliary selective controls 172, 173 and 174 ineffective or inoperative. Thus inadvertent or accidental energization of the magnet circuit is prevented and the magnet circuit remains inoperative until the pull rod 109 of the main power control unit 108 is reset to its operative position and the magnet circuit is simultaneously reconditioned for further operation by the selective controls 172, 173 and 174.

Briefly summarizing the operation of the controls and associated braking instrumentalities, let it first be assumed that the knitting machine is at a standstill. To start the machine, the operator will grasp the brake lever handle 16 in one hand and raise the brake lever, holding the same

in an elevated position while drawing the pull rod 109 of the main control unit 108 in a forward direction with the aid of the handle 112 which may be conveniently grasped by the other hand of the operator. On completion of these operations the brake lever 14 will be held in an elevated position by engagement of the pin 104 with the upper end of the arm 103 which forms a part of the brake tripping mechanism, maintaining the brakes associated with the needle cylinder 20 and which the take-up mechanism 38 in a released condition, while the power supply to the driving motor 13 is energized through closing of the switch on engagement of the switch blade 130 with the contact members 137, 137. The machine will continue to operate so long as the power supply is maintained and the pull rod 109 is held in its operative position by engagement of the trip latch 146 with the dog 141. To stop the machine at will, the operator may do so by simply depressing the stop button 172 which causes the magnet 158 to be energized. On energization of the magnet 158, the armature 155 is attracted, releasing the trip latch 146 and thereby allowing the spring 113 to force the pull rod 109 rearwardly, thereby breaking the power circuit at the contacts 137, 137, and interrupting the power drive. A short coil spring 113' on the pull rod 109 and interposed between the crosshead 125 and the rear wall of the casing 110 cushions the return movement of the pull rod 109 and the parts carried thereby.

Instead of interrupting the power drive through manual operation of the stop button 172, let it be assumed that one of the main threads T or any other of the thread feeds breaks, then in that event, the magnet 158 will be energized by automatic operation of the thread stop motion device 173. A similar magnet energization is accomplished by the thread stop motion device 173 in case of undue tension on the thread or some other imperfection occurs in any one of the thread feeds.

On the other hand, if an imperfection occurs in the fabric F as it is knitted, the magnet 158 will be energized by automatic operation of the fabric stop motion device 174.

Whenever the magnet 158 is energized by any of the selective controls 172, 173 and 174, the trip latch 146 will be released, allowing the pull rod 109 to move to its inoperative or power interrupting position under the influence of the spring 113. On movement of the pull rod 109 to its inoperative position just referred to, the pin 116 carried by the pull rod acts upon the lever arm 117 to rock the shaft 100 connected to this arm in a direction which moves the other arm 103 from beneath the pin 104 on the brake lever 14. This displacement of the arm 103 from engagement with the pin 104 causes the brakes for both the needle cylinder and the take-up mechanism to be automatically applied under the influence of the spring 97, thereby abruptly stopping the machine substantially simultaneously with the interruption of the power drive at the motor 13. Restoration of the power drive and resetting of the brakes in their released condition may then be accomplished by performing the same operations as previously described with respect to starting of the machine.

While the specific details have been herein shown and described, the invention is not confined thereto, as changes and alterations may be made without departing from the spirit thereof as defined by the appended claims.

What I claim as new and desire to secure by Letters Patent is:

1. A knitting machine, comprising a rotatable needle cylinder, thread feeding and knitting instrumentalities associated therewith, a fabric take-up mechanism axially spaced from the needle cylinder and rotatable therewith, driving means for imparting rotation to the needle cylinder and take-up mechanism aforesaid, control means for controlling operation and interruption of operation of the driving means, and brake means for separately applying braking force to the needle cylinder and take-up mechanism respectively on interruption of operation of the driving means.

2. A knitting machine, comprising a rotatable needle cylinder, thread feeding and knitting instrumentalities associated therewith, a fabric take-up mechanism axially spaced from the needle cylinder and rotatable therewith, driving means for imparting rotation to the needle cylinder and take-up mechanism aforesaid, control means for controlling operation and interruption of operation of the driving means, and brake means for applying braking force to the needle cylinder and take-up mechanism on interruption of operation of the driving means, said brake means including a brake drum operatively connected to the needle cylinder and a separate brake drum operatively connected to the take-up mechanism, and means coactively associated with the respective brake drums for simultaneous braking engagement therewith.

3. A knitting machine, comprising a rotatable needle cylinder, thread feeding and knitting instrumentalities associated therewith, a fabric take-up mechanism axially spaced from the needle cylinder and rotatable therewith, driving means for imparting rotation to the needle cylinder and take-up mechanism aforesaid, control means for controlling operation and interruption of operation of the driving means, and brake means for applying braking force to the needle cylinder and take-up mechanism on interruption of operation of the driving means, said brake means including a brake element operatively connected to the needle cylinder for rotation therewith, a separate brake element operatively connected to the take-up mechanism for rotation with the latter, and additional braking instrumentalities associated with the respective brake elements aforesaid and operative on engagement with the latter to produce a braking action on both the needle cylinder and take-up mechanism.

4. A knitting machine, comprising a rotatable needle cylinder, thread feeding and knitting instrumentalities associated therewith, a fabric take-up mechanism axially spaced from the needle cylinder and rotatable therewith, driving means for imparting rotation to the needle cylinder and take-up mechanism aforesaid, control means for controlling operation and interruption of operation of the driving means, and brake means for applying braking force to the needle cylinder and take-up mechanism on interruption of operation of the driving means, said brake means including a brake element operatively connected to the needle cylinder for rotation therewith, a separate brake element operatively connected to the take-up mechanism for rotation with the latter, additional braking instrumentalities associated with the respective brake elements aforesaid and operative on engagement

with the latter to produce a braking action on both the needle cylinder and take-up mechanism, and actuator means common to the braking instrumentalities associated with both braking elements, for controlling the braking action of the needle cylinder and take-up mechanism.

5. A knitting machine, comprising a rotatable needle cylinder, thread feeding and knitting instrumentalities associated therewith, a fabric take-up mechanism axially spaced from the needle cylinder and rotatable therewith, driving means for imparting rotation to the needle cylinder and take-up mechanism aforesaid, control means for controlling operation and interruption of operation of the driving means, and brake means for applying braking force to the needle cylinder and take-up mechanism on interruption of operation of the driving means, said brake means including trip means operative to set position by the control means for the driving means, for normally holding the brake means in a released condition during operation of the driving means, in combination with additional trip means for normally holding the control means on operation of the control means to cause rotation of the needle cylinder in a position to cause operation of the driving means, and selectively operable auxiliary trip means for actuating the last-mentioned trip means to release the control means and interrupt operation of the driving means, and consequently cause tripping of the brake release holding trip means and application of braking force to the needle cylinder and take-up mechanism.

35. 6. A stop-motion device for knitting machines having a rotatable needle cylinder, thread feeding and knitting instrumentalities associated therewith, a fabric take-up mechanism axially spaced from the needle cylinder and rotatable therewith, and power driving means for imparting rotation to the needle cylinder and take-up mechanism, said stop-motion comprising a shiftable main control member manually operable to a position causing operation of the power driving means, means for normally yieldably urging the main control member to another position causing interruption of the operation of the power driving means, latch means automatically operable upon manual operation of the main control member to hold the main control member in such position, and auxiliary control means selectively operable by the thread feed, the fabric, and manually, to trip the latch means and allow movement of the main control member to its second-mentioned position interrupting operation of the power driving means, in combination with brake means for automatically applying braking force to the needle cylinder and take-up mechanism responsive to selective operation of the auxiliary control means aforesaid.

7. Apparatus as defined in claim 6, wherein certain of the selectively operable auxiliary control means includes yieldable means releasably engaging the thread in the thread feed for producing a substantial slack in the thread when tension on the thread exceeds a predetermined amount.

8. A knitting machine, comprising a rotatable needle cylinder, thread feeding and knitting instrumentalities associated therewith, a fabric take-up mechanism axially spaced from the needle cylinder and rotatable therewith, driving means for imparting rotation to the needle cylinder and take-up mechanism aforesaid, said

driving means being electrically powered by an electric power circuit, control means for controlling operation and interruption of operation of the driving means, said control means including a shiftable actuator member, brake means for applying braking force to the needle cylinder and take-up mechanism on interruption of operation of the driving means, switch means disposed in the power circuit and operable by the actuator member, latch means for holding the shiftable actuator member in a position closing the switch means in the power circuit to energize the driving means, and means for tripping the latch means to release the actuator member to allow further movement of the latter to open the switch means and interrupt the power circuit to the driving means.

9. A knitting machine, comprising a rotatable needle cylinder, thread feeding and knitting instrumentalities associated therewith, a fabric take-up mechanism axially spaced from the needle cylinder and rotatable therewith, driving means for imparting rotation to the needle cylinder and take-up mechanism aforesaid, said driving means being electrically powered by an electric power circuit, control means for controlling operation and interruption of operation of the driving means, said control means including an actuator member manually shiftable in one direction and having yieldable means normally urging the same in the opposite direction, brake means for applying braking force to the needle cylinder and take-up mechanism on interruption of operation of the driving means, switch means disposed in the power circuit and operable by the actuator member, latch means for holding the shiftable actuator member in a position closing the switch means in the power circuit to energize the driving means on manual shifting of the actuator member, and means for tripping the latch means to release the actuator member to allow shifting movement of the latter by the yieldable means to open the switch means and interrupt the power circuit to the driving means.

10. A knitting machine, comprising a rotatable needle cylinder, thread feeding and knitting instrumentalities associated therewith, a fabric take-up mechanism axially spaced from the needle cylinder and rotatable therewith, driving means for imparting rotation to the needle cylinder and take-up mechanism aforesaid, said driving means being electrically powered by an electric power circuit, control means for controlling operation and interruption of operation of the driving means, said control means including an actuator member manually shiftable in one direction and having yieldable means normally urging the same in the opposite direction, brake means for applying braking force to the needle cylinder and take-up mechanism on interruption of operation of the driving means, switch means disposed in the power circuit and operable by the actuator member, latch means for holding the shiftable actuator member in a position closing the switch means in the power circuit to energize the driving means on manual shifting of the actuator member, and means for tripping the latch means to release the actuator member to allow shifting movement of the latter by the yieldable means to open the switch means and interrupt the power circuit to the driving means, said latch tripping means including an auxiliary electrical control circuit having electro-magnetic means arranged therein for actuating the latch means to its tripped position.

11. A knitting machine, comprising a rotatable needle cylinder, thread feeding and knitting instrumentalities associated therewith, a fabric take-up mechanism axially spaced from the needle cylinder and rotatable therewith, driving means for imparting rotation to the needle cylinder and take-up mechanism aforesaid, said driving means being electrically powered by an electric power circuit, control means for controlling operation and interruption of operation of the driving means, said control means including an actuator member manually shiftable in one direction and having yieldable means normally urging the same in the opposite direction, brake means for applying braking force to the needle cylinder and take-up mechanism on interruption of operation of the driving means, switch means disposed in the power circuit and operable by the actuator member, latch means for holding the shiftable actuator member in a position closing the switch means in the power circuit to energize the driving means on manual shifting of the actuator member, and means for tripping the latch means to release the actuator member to allow shifting movement of the latter by the yieldable means to open the switch means and interrupt the power circuit to the driving means, said latch tripping means including an auxiliary electrical control circuit having electro-magnetic means and an associated controlling device arranged therein for actuating the latch means to its tripped position, and means controlled by shifting of the actuator member to its power circuit interrupting position for rendering the controlling device for the electro-magnetic means inoperative until restoration of the actuator member to its power circuit closing position.

12. A knitting machine, comprising a rotatable needle cylinder, thread feeding and knitting instrumentalities associated therewith, a fabric take-up mechanism axially spaced from the needle cylinder and rotatable therewith, driving means for imparting rotation to the needle cylinder and take-up mechanism aforesaid, said driving means being electrically powered by an electric power circuit, control means for controlling operation and interruption of operation of the driving means, said control means including an actuator member manually shiftable in one direction and having yieldable means normally urging the same in the opposite direction, brake means for applying braking force to the needle cylinder and take-up mechanism on interruption of operation of the driving means, switch means disposed in the power circuit and operable by the actuator member, latch means for holding the shiftable actuator member in a position closing the switch means in the power circuit to energize the driving means on manual shifting of the actuator member, and means for tripping the latch means to release the actuator member to allow shifting movement of the latter by the yieldable means to open the switch means and interrupt the power circuit to the driving means, said latch tripping means including an auxiliary electrical control circuit having electro-magnetic means and associated selectively operable controlling devices arranged therein for actuating the latch means to its tripped position.

13. A stop-motion device for knitting machines having a rotatable needle cylinder, thread feeding and knitting instrumentalities associated therewith, a fabric take-up mechanism axially spaced from the needle cylinder and rotatable therewith, and power driving means for

imparting rotation to the needle cylinder and take-up mechanism, said stop motion comprising a main control member normally effective to maintain operation of the power driving means, a plurality of auxiliary control means selectively operable to render the main control member ineffective to maintain operation of the power driving means, at least one of said selective auxiliary control means being automatically operable responsive to excessive tension on the thread of a thread feed, and cooperative rotary members engaging the thread of the thread feed at opposite sides thereof and disposed intermediate the tension responsive auxiliary control means and the needles on the needle cylinder for relieving the needles of drag of the thread and for uniformly feeding the thread to the needles, said cooperative rotary members being driven by operative engagement with the needles.

14. A stop-motion device for knitting machines having a rotatable needle cylinder, thread feeding and knitting instrumentalities associated therewith, a source of thread supply disposed below the needle cylinder in radially outwardly spaced relation to a projection of the central axis of the needle cylinder, a fabric take-up mechanism axially spaced above the needle cylin-

der and rotatable therewith, and power driving means for imparting rotation to the needle cylinder and take-up mechanism, said stop motion comprising a shiftable main control member, trip means for holding said main control member in one position to cause rotation of the needle cylinder and take-up mechanism by the power driving means, and thread tension responsive means positioned below the needle cylinder between the source of thread supply and the thread feeding and knitting instrumentalities for actuating the trip means aforesaid to permit shifting movement of the main control member to a drive-interrupting position, said thread tension responsive means including means disposed below the needle cylinder in proximity to the projected central axis thereof and displaceably receiving the thread at the innermost point of a radially inwardly extended bight in the thread for producing slack in the thread when the thread tension exceeds a predetermined limit sufficiently to displace the thread from the latter thread receiving means, whereby to prevent breakage of the thread during actuation of the trip means and main control member to cause interruption of the drive as aforesaid.

WILLIS A. INGALLS.
